(57) **CLAIM**

The ornamental design for a sock with scrunchie strap, as shown and described.

DESCRIPTION

FIG. 1 is a perspective view showing a first embodiment of my new sock with scrunchie strap design in use;

FIG. 2 is a top view thereof;

FIG. 3 is a bottom view thereof;

FIG. 4 is a left side view thereof;

FIG. 5 is a right side view thereof;

FIG. 6 is a front view thereof;

FIG. 7 is a rear view thereof;

FIG. 8 is a perspective view showing a second embodiment of my new sock with scrunchie strap design in use;

FIG. 9 is a top view thereof;

FIG. 10 is a bottom view thereof;

FIG. 11 is a left side view thereof;

FIG. 12 is a right side view thereof;

FIG. 13 is a front view thereof; and,

FIG. 14 is a rear view thereof.

The evenly dashed broken lines depict environmental subject matter, and form no part of the claimed design. The dash-dot-dash broken lines depict the cut line and form no part of the claimed design.

1 Claim, 8 Drawing Sheets
